CHECK FOR CHECK CONTROLLED APPARATUS

Aaron A. Knee, Charlotte, N. C., assignor to
 Vanak Corporation, Charlotte, N. C., a corporation of North Carolina

Application January 14, 1937, Serial No. 120,490

2 Claims. (Cl. 194—4)

This invention relates to a coin or check which is adapted to be used in slot machines, check testing apparatus and the like, and more especially to a check which is adapted for use with a mechanism shown and described in my co-pending patent application Serial No. 32,420, filed July 20, 1935, Patent No. 2,073,392 of March 9, 1937.

In many States of the Union there is an existing law which prohibits the use of any check in a slot machine, game board, check testing apparatus and the like, which is of the same diameter as a genuine coin. Therefore, it is necessary to substitute therefor a coin or check which is of slightly less or slightly larger diameter than that of a genuine coin. Since the check testing apparatus shown in my said co-pending patent application has means for testing the surface configurations, the thickness, and the diameter of a coin before accepting the same, it is necessary to provide a coin or check which will comply with the tests applied to a coin or slug inserted therein by this apparatus.

As stated in my co-pending patent application, the feelers, which engage the faces of the coin or check for testing the surface configuration are equally spaced in a circular row so that the ends thereof will engage the surface of the coin or check. If all of the feelers are actuated exactly the same amount as a result of all the points of contact being at the same level on the face of the coin, then the coin will be rejected. In order for the coin to be tested as to its surface configuration, some of the feelers will have to be actuated more than the others as a result of the irregularities on the face of the coin. In order to insure that this effect will be produced on the feelers, the coin or check has been designed so that certain feelers will be sure to hit a high spot on the surface of the coin and certain of the feelers will be sure to engage a depression thereby actuating the feelers an unequal amount.

It is therefore, an object of this invention to provide a circular check for use in a check testing apparatus having a plurality of spaced depressions therein arranged in a circle whose center is the center of the circular row of feelers which are adapted to be pressed against said check, the feelers and the depressions being unlike in number to insure that the feelers will be actuated unevenly to cause the check to pass the surface configuration test.

Some of the objects of the invention having been stated, other objects will appear as the description proceeds when taken in connection with the accompanying drawing, in which:—

Figure 1 is an isometric view showing one side of the invention;

Figure 2 is an isometric view showing the opposite side of the invention from that shown in Figure 1;

Figure 3 is a sectional view taken along line 3—3 in Figure 2;

Figure 4 is an elevation of a check similar to that shown in Figures 1, 2 and 3, but having the depressions on opposed sides thereof in a staggered relation to each other;

Figure 5 is an elevation of a slightly different modified form of the invention constructed along the same lines as that shown in Figure 4;

Figure 6 is a sectional view taken along line 6—6 in Figure 5.

Referring more specifically to the drawing, the numeral 10 denotes a suitable coin or check which is adapted to be used in a slot machine, check testing apparatus and the like, said coin 20 having a plurality of evenly spaced depressions 11 on the face thereof and a plurality of similarly arranged depressions 12 are disposed exactly opposite each other on the faces of the coin, thereby providing ridges or high places 13 and 14 between 25 these cavities. These high places or ridges 13 and 14 are substantially at the same elevation or level as the other surfaces of the coin. The feelers in my co-pending application, Serial No. 32,420, are evenly numbered and evenly spaced, 30 there being ten feelers concentrically spaced. The coin 10 is placed in the apparatus with the central portion thereof placed in coinciding relation with the center of the circular row of feelers.

It will be noted that in the coin 10 there are 35 nine evenly spaced concentric cavities 11 and nine cavities 12. When the coin is placed in testing position in the apparatus and the testing means or feelers are thrown into operation, some of the feelers will be sure to contact the high 40 places 13 or 14 and some will be sure to engage the cavities 11 or 12, since the depressions and feelers are equally spaced on the check testing apparatus and coin respectively, but the number of feelers and depressions being unlike.

Figure 4 shows a slightly modified form of the invention in which the coin 15 has a plurality of evenly spaced depressions 16 in one face thereof and a plurality of evenly spaced depressions 17 on the opposite face; said depressions 16 on 50 one face of the coin 15 being in staggered relation to depressions 17 on the other face. There are a plurality of high places 18 disposed between the depressions 16 and 17, which high places are substantially at the same elevation as the other sur- 55

faces of the coin 15. Since the surface configurations of only one face of the coin are tested when the coin is inserted into the check testing apparatus, it is evident that the relative position 5 of the depressions on opposed side of the coin to the depressions on the tested side, does not materially matter except from a manufacturer's standpoint. In many cases it is desirable to form the stamps or dies in such a manner so that 10 the coin or check will be stamped with the depressions bearing a staggered relation to each other on opposed faces of the coins.

Figure 5 shows another slightly modified form in which a coin 20 has a plurality of concentrically spaced circular depressions 21 disposed in 15 one face thereof and a plurality of circular spaced depressions 22 disposed in its other face. These depressions on the opposed sides of the face bear a staggered relation to each other as is shown in 20 Figure 4. Likewise, in this form, the portion 23 of the coin which is disposed between the depressions 21 or 22 is at the same level as the other surfaces of the coin.

It is therefore, seen that I have provided a 25 check or coin of predetermined thickness and diameter, said coin having a plurality of radially disposed depressions in each face thereof with ridges or high spots between said depressions so that the coins may properly comply with surface configuration tests applied in any coin testing apparatus having a plurality of radially disposed feelers for testing the surface configura- 30

tions which feelers are of uneven number from the number of depressions in the face of the coin tested.

In the drawing and specification there has been 5 set forth a preferred embodiment of the invention, and although generic terms are employed, they are used in a generic and descriptive sense only, and not for purposes of limitation, the scope of the invention being set forth in the appended claims. 10

I claim:

1. A check for use in a check controlled apparatus wherein a plurality of feelers are arranged in a circle for engaging one side of the check near its periphery, said check having a plane surface on each side thereof and each plane surface having a plurality of spaced depressions therein arranged near the periphery of the check in a circle whose center is the center of the check, the spaced depressions on one side of the check 20 being disposed in a different radial plane from the depressions on the other side of the check. 15

2. A circular check for use in check controlled apparatus and having a pair of opposed plane side surfaces each provided with a plurality of equally spaced depressions arranged near the periphery of the check in a circle whose center is disposed at the center of the check, the spaced depressions on one side of the check being disposed in a different radial plane from the depressions on the 30 other side of the check. 25
